C. E. Rombough

J. A. Murphy, Jr. Attorney

UNITED STATES PATENT OFFICE.

CHARLES E. ROMBOUGH, OF LONG BEACH, CALIFORNIA.

HATPIN.

1,420,500.

Specification of Letters Patent. Patented June 20, 1922.

Application filed June 8, 1921. Serial No. 475,999.

To all whom it may concern:

Be it known that I, CHARLES E. ROMBOUGH, a subject of the King of Great Britain, residing at Long Beach, in the county of Los Angeles and State of California, have invented certain new and useful Improvements in Hatpins; and I do hereby declare the following to be a full, clear, and exact description of the invention, such as will enable others skilled in the art to which it appertains to make and use the same.

This invention relates to certain new and useful improvements in a hat pin and has for its primary object the provision of an improved hat pin of the form disclosed in my Patent No. 1,370,559, and which may be readily attached to a hat of conventional form without injury thereto.

The invention has for another object the provision of a hat pin of the character stated which will be constructed in such a manner that the stem of the pin may revolve through the crown of the hat and the coil of the pin with the pointed free end thereof may work through a guard and shield plate secured to the inner face of the crown of the hat, whereby practically all of the coil of the pin may be withdrawn to position back of the guard and shield plate when it is desired to withdraw the pin from the wearer's hair and remove the hat, thereby reducing to the minimum liability of the pin being caught in the wearer's hair and causing the hair to be deranged.

The invention has for another object the provision of a hat pin of the character stated which will be of extremely simple and inexpensive construction as well as highly efficient in use and which may be applied to the various types of ladies' hats without alteration thereof or injury to the hat.

The invention has for a further object the provision of a hat pin of the character stated in which the guard and shield plate may be composed of any suitable material and will be provided with guide openings and lugs for the coil of the hat pin as well as a stop lug to limit movement of the pin in one direction, so that the point of the pin will not be drawn back of the shield or guard plate.

The invention has for a still further object the provision of a hat pin of the character stated which may be readily operated to either secure the hat in position or permit removal of the same from the wearer's head, as desired, by proper manipulation of a knob or other pin head located externally of the hat.

With the foregoing and other objects in view as will appear as the description proceeds, the invention consists in the novel construction, combination and arrangement of cooperating elements as hereinafter more specifically set forth, claimed and shown in the accompanying drawings forming a part of the present application and in which:

Figure 1 is a fragmentary sectional view of a hat with my invention applied thereto,

Figure 2 is a bottom plan view illustrating the pin in an operative position,

Figure 3 is a side elevation illustrating the device,

Figure 4 is a top plan view, illustrating a modified form of my invention and showing the pin partly in dotted lines,

Figure 5 is a side elevation illustrating the same,

Figure 6 is a detail view illustrating a combined stop and pivot tongue for the pin.

Referring more in detail to the drawings in which similar reference characters designate corresponding parts throughout the several views, 1 indicates the stem of the hat pin which is extended through a suitable opening 2, preferably formed centrally in the crown of the hat as shown in the drawings. A knob or pin head 3 is mounted on the outer or upper extremity of the stem 1 and the hat pin may be readily operated by proper manipulation of the knob or pin head 3, as will be readily understood as the description proceeds. The material from which the pin is formed is extended at a right angle, as shown at 4 from the inner end of the stem 1 and the material is then curved to form the coil or hook 5 of the hat pin with the pointed free end 6, as clearly shown in the drawings. The shield or guard plate 7 constructed of celluloid, tin or any other suitable material is secured to the inner face of the hat crown around the opening 2, by stitching along the edge of the shield or guard plate 7 and desig-

nated by the numeral 8, or by any other suitable and well known means of securing the member to the inner face of the hat crown. The hat crown may be designated by the 5 numeral 9.

It will be understood that the straight portion 4 of the hat pin is inwardly of the guard plate or shield 7 and this guard plate or shield 7 has a substantially U-shaped incision 10 formed therein and the material between the lines of the incision bent inwardly to form the guide lug 11. This guide lug 11 is perforated as shown at 12, so that the coil 5 of the hat pin may work back 10 and forth through the same. A second U-shaped incision 14 is formed in the guard plate adjacent the first mentioned incision and the material between the lines of the second incision bent inwardly to form a 15 non-perforated guide lug which will direct the coil 5 of the hat pin outwardly to ride over this guide lug 15. Both of the lugs referred to are formed adjacent the outer 20 edge of the shield or guard plate 7. A third incision of U-shaped form is made in 25 the guard plate or shield 7 and designated by the numeral 16 and the material between the lines of this U-shaped incision bent inwardly to form a stop lug 17 to limit movement of the hat pin in one direction so that the point 6 of the coil 5 will not be drawn inwardly of the guard plate or shield 7 but will stop at a point about opposite the guide lug 15. This movement of the hat pin in 30 this direction is limited by engagement of the straight portion 4 with the stop lug 17 as the pin is rotated by means of the knob or pin head 3 for the purpose of withdrawing the coil 5 from the wearer's hair and 35 drawing the coil into the pocket provided therefor inwardly of the guide plate or shield 7 or between the guard plate or shield 7 and the hat crown. While the shield or 40 guard plate 7 is shown as being constructed of a transparent material such as celluloid, tin or any other suitable material may be employed and while the guide lugs for the coil 5 are shown as being struck out from the material of the guard plate or shield 7 and bent 45 inwardly and extended circumferentially or parallel with the straight edge of the guard plate or shield 7 and the stop lug 16 is shown as being extended inwardly toward the center of the guard plate or shield 7, the three 50 lugs may be formed in any other suitable and well known manner.

Referring to my modified form of invention as shown in Figures 4 to 6, the guard plate or shield 18 has a centrally located 55 combined stop and pivot tongue 19 which is struck up from the shield 18 and has an opening 20 to receive the stem 21 of the hat pin 22. The hat pin 22 has a short straight portion 23 that terminates into the coil portion

24. The combined stop and pivot tongue 19 is substantially hook-shaped and is adapted 65 to limit the rotation of the hat pin in either direction by the hat pin engaging in a notch 25 when moved in one direction and when moved in an opposite direction is adapted to 70 engage the combined stop and pivot tongue where it forms onto the plate or shield 18. The pin when in an inoperative position, the coil portion thereof lies between the hat and the shield or plate and when moved into an 75 operative position, the coil portion moves through a slot 26 in the plate or shield to occupy a position at the opposite side of the shield or plate so as to engage in the hair of the wearer.

While I have shown and described the preferred embodiment of my invention, it will be understood that minor changes in construction, combination and arrangement of parts may be made without departing from 85 the spirit and scope of the invention as claimed.

What is claimed is:—

1. A hat pin guard comprising the combination with a guide and guard plate secured to the inner face of a hat crown and having guide lugs and a stop lug formed therewith, of a hat pin stem rotatably mounted through said crown of the hat, a straight portion of the hat pin extended from the inner end of said stem, a coil portion of the hat pin extended from said straight portion and working through and over the guide lugs of the guard shield, said straight portion engaging one of said guide lugs to limit movement of the hat pin in one direction, said straight portion engaging the stop lug to limit movement of the hat pin in the reverse direction, and an operating knob carried by said stem outwardly of said hat crown.

2. A hat pin comprising a shield, a tongue struck up from said shield, a pin extending through the tongue and having a coiled hair engaging portion adapted to move from one side of the shield to the other by the rotation of the pin, said tongue adapted to limit the rotation of the pin in one direction, said shield having a slot to permit the coil portion to move from one side to the other side thereof.

3. A hat pin structure including a guard plate having an opening therethrough, a pin having a hair-engaging coil for normal retention on one side of the plate, a lug 120 extending from said side of the plate, said coil being slidably mounted in said lug, said coil being rotatable for projection through said opening to the other side of the plate when the hat with which it is associated is worn.

4. A hat pin structure including a guard plate having an opening therethrough, a

pin having a hair-engaging coil for normal retention on one side of the plate, a lug extending from said side of the plate, said coil being slidably mounted in said lug, said coil being rotatable for projection through said opening to the other side of the plate when the hat with which it is associated is worn, and said plate having an opening at

a distance from the lug through which the coil is projected. 10

In testimony whereof I affix my signature in presence of two witnesses.

CHARLES E. ROMBOUGH.
